UNITED STATES PATENT OFFICE.

SELDEN G. WARNER, OF WEST ORANGE, NEW JERSEY, ASSIGNOR TO NEW JERSEY PATENT COMPANY, OF WEST ORANGE, NEW JERSEY, A CORPORATION OF NEW JERSEY.

LAMP.

Application filed February 24, 1920. Serial No. 360,697.

To all whom it may concern:

Be it known that I, SELDEN G. WARNER, a citizen of the United States, and a resident of West Orange, Essex County, New Jersey, have invented certain new and useful Improvements in Lamps, of which the following is a description.

My invention relates to lamps, and more particularly to an improved form of lamp designed especially for use in railway signalling although the same is applicable to many other uses.

One of the objects of the invention is to provide an improved construction employing a lamp in conjunction with a lens for projecting the light emitted by the lamp, whereby the lamp may be readily, quickly and accurately adjusted to a position with its illuminating center at a predetermined position with respect to the lens, as, for example, at the back focal point of the lens, and whereby after the adjustment of the lamp the latter will be rigidly maintained in fixed adjusted position with respect to the lens regardless of any deformation or variation of the housing or casing in which the lens is mounted.

My invention also consists in an improved fixture or attachment for carrying the lamp and which is adapted to be rigidly and directly attached to the lens in conjunction with which the lamp is intended to be used. This fixture or attachment is an important feature of my invention, and it is especially applicable for use as an "adapter" enabling the oil lamps of the standard form of railway signal lamps to be readily replaced by electric lamps with the illuminating center or filament of the latter adjusted to and rigidly maintained at any desired point with respect to the lens, but preferably the back focal point of the lens. Practically all electric lamp adapters for this purpose now on the market are designed to be mounted on or built up from the bottom or base of the lamp housing, and accordingly provision must be made therein to compensate for the numerous variations which exist in the size, shape, etc. of the crudely and inaccurately made lamp housings even where they are supposed to be identical. Moreover, any variation in or deformation of the lamp housing which takes place after the installa-

tion of an electric lamp adapter mounted on or built up from the bottom of the housing, and after the adjustment of the electric lamp carried thereby to a focal point of the lens, is likely to throw the electric lamp out of focus with the lens. With my adapter, however, these disadvantages are entirely obviated as the same is located directly from and rigidly attached to the lens itself, the only part of the complete lamp not subject to unusual variations.

Other features of my invention reside in the construction of parts and combinations of elements hereinafter more specifically described and claimed.

In order that my invention may be more clearly understood, attention is directed to the drawing accompanying and forming a part of this specification and in which:

Figure 1 is a view in side elevation, partly in section and partly broken away, of a railway signal lamp with one embodiment of my invention applied thereto;

Fig. 2 is an enlarged view in perspective showing my improved fixture or attachment applied to a lens such as is used in the type of signal lamp shown in Fig. 1;

Fig. 3 is an enlarged sectional view on line 3-3 of Fig. 1, the lamp being omitted;

Fig. 4 is a sectional view on line 4-4 of Fig. 3;

Fig. 5 is a fragmental view of a modification; and

Fig. 6 is a view similar to Fig. 5 of a further modification.

Referring to the drawing, and especially to Figs. 1 to 4, reference character 1 represents the usual sheet-metal housing or casing of the standard form of railway signal lamp, provided with the usual bottom or base 2 and the slidable door 3 for rendering the interior of the housing accessible. The side or vertical wall of the housing is provided with an opening surrounded by an annular flange 4 having a shouldered rim 5, the latter constituting a bezel for the reception of the usual corrugated spherical lens 6. Such a lens is commonly known as a "semaphore" lens and will hereinafter be so designated both in the specification and claims. The bezel 5 has rotatably mounted thereon, the usual split locking ring 7 provided with a number of spaced pins 8 ex-

tending through inclined slots or openings 9 provided in the bezel 5, only one of each of such pins and slots being shown. The pins 8 are of such length as to engage the outer 5 spherical surface of the lens 6 whereby the turning of the ring 7 will grip or loosen the lens in the bezel according to the direction in which the ring is turned. A screw 10 extending through opposed lugs provided on 10 the ring 7 where split, and having threaded engagement with one of such lugs, serves to lock the lens 6 in the bezel after the same has been securely gripped in position by turning the ring 7.

15 My improved attachment or adapter consists of a frame or fixture A comprising a suitable rigid supporting member, shown herein as a ring 11, the substantially rigid rods or legs 12 connected at one end to the 20 supporting member or ring 11 and preferably free at the other end, and a lamp support preferably formed integrally with the supporting member or ring 11 of the frame. I preferably employ three legs and prefer- 25 ably connect the same to the ring or supporting member 11 at substantially equi-spaced points. It is thus apparent that the frame as shown constitutes a tripod. The rods or legs 12 are preferably, though not necessarily, rigidly secured or fixed at one end to the 30 ring or supporting member 11, as shown in Figs. 1 and 2. When so fixed to the supporting member 11, the rods or legs employed are slightly resilient, are preferably, 35 though not necessarily, of substantially the same length and are preferably attached to the supporting member so as to diverge in a direction away from such supporting member. Where my attachment or adapter is 40 designed to be applied to a "semaphore" lens, such as shown in Figs. 1 and 2, and the rods or legs 12 thereof are rigidly fixed to the supporting member 11, these rods are so arranged or diverge to such a degree that 45 a circle circumscribed about the free ends thereof when the rods assume their normal position, will be of a diameter slightly greater than the outside diameter of the outermost annular groove 30 of the lens 6. Each 50 of the rods 12 is provided adjacent its free end with a boss or collar 13 having a preferably somewhat resilient laterally and outwardly extending projection 14. The support for the lamp preferably comprises an 55 L-shaped bracket 15 attached to and preferably formed integrally with the supporting member or ring 11, and the base 16 of which is provided with suitable means for supporting a lamp, such as a low-voltage in- 60 candescent lamp 17 having a small coil filament 18. The base 16 is preferably formed of slightly resilient material and is split or kerfed longitudinally and substantially centrally thereof as shown at 19. Intermediate 65 the ends of the split or kerf 19, the base 16

of the bracket 15 is provided with a ball socket 20 in which is mounted a ball 21 formed of slightly resilient material having a preferably central cylindrical opening 22 extending therethrough and provided with 70 a split or kerf 23. The base 16 of bracket 15 is preferably substantially parallel to the axis of the tripod frame A and the axis of the socket 20 extends transversely of and preferably substantially at right angles to 75 the axis of the said frame A. The cylindrical lamp-stem 24 through which the leads 25 and 26 extend, is mounted in and extends through the cylindrical opening 22 in the ball 21. The base 16 of the bracket is pro- 80 vided with opposed lugs 27 and 28 at the outer end of the split or kerf 19, a bolt 29 extending loosely through the lug 27 and being threaded into the lug 28. It will be apparent that on sufficiently tightening the 85 bolt 29, the lamp stem 24, ball 21 and bracket 15 will be rigidly locked together against all relative movement. It will also be apparent that upon loosening the bolt 29, the lamp 17 is universally adjustable with re- 90 spect to the bracket 15, for it may then be pivotally moved in any direction and by reason of the engagement of the lamp stem 24 with the opening in the ball 21, the lamp may also be turned and moved longitudinally in either direction in the ball 21. The construction just described constitutes a very efficient and simple mounting for the lamp whereby the same may be readily ad- 95 justed in any desired manner and whereby when adjusted the same may be rigidly locked in adjusted position by manipulation of a single member. 100

In applying my attachment or adapter to a semaphore lens such as shown in Figs. 1 and 2, the rods or legs 12 are forced towards each other a slight distance at their free ends and sprung into the outer annular groove 30 of the lens, and the adapter is then rigidly secured in fixed position with 110 respect to the lens with the free ends of the rods in firm engagement with the bottom and side walls of said groove. In the construction shown in Figs. 1 and 2 this is ac- 115 complished by tightening the clamping ring 7 by turning the same in the proper direction. The tightening of this ring forces the lens 6 inwardly of the bezel 5, thereby forcing the frame A in the same direction which results in the flexing of the resilient 120 lateral projections 14 of the legs 12 towards the outer peripheral portion of the lens by reason of the engagement thereof with the shoulder 5' of the bezel. It will be apparent that the frame A may thus be very rigidly 125 secured to the lens in fixed position with respect thereto. The lamp 17 may now be readily adjusted so as to bring the illuminating center or filament 18 thereof to any desired point with respect to the lens 6, such 130

as the back focal point thereof, and then rigidly secured in said position by tightening the bolt 29. Where it is desired to adjust the lamp filament to the back focal point of the lens in order to most effectively project the light to a distance, as is usually the case where signal lamps are employed, the lamp 17 is preferably adjusted so that the small coil filament 18 will be substantially at right angles to the axis of the lens or, in other words, broad-side to the lens. With this arrangement, from an illuminating standpoint, I am enabled to obtain with a low-voltage incandescent lamp having a very small filament, results at least as effective as those obtained by the usual oil lamps the flames of which are, comparatively speaking, very wide.

An important feature of my invention is that once the illuminating center of the lamp has been adjusted to a certain position with reference to a lens and the lamp secured in adjusted position to the fixture or attachment by tightening the bolt 29, the attachment may be removed from the lens and then again applied thereto or to any other similar lens with the assurance that the illuminating center or filament of the lamp will occupy the same position with respect to such lens.

While I have described the preferred form of attachment or adapter embodying my invention, the same is subject to numerous modifications. For example, while the legs 12 of the frame of the adapter or attachment shown are rigidly attached at one end to the supporting member or ring 11, this, as has been previously indicated, is not at all essential where a plurality of legs are employed for equally good results may be obtained by the use of any frame which would be maintained rigid with respect to a lens when the legs or other parts thereof adapted to engage or coact with the lens are secured to or against the latter in fixed position with respect thereto.

In Figs. 1 and 2 I show one form of my improved attachment, fixture or adapter applied to a "semaphore" lens. Adapters in accordance with my invention, however, are capable of being applied to other types of lenses and may also be secured to lenses in many ways other than that shown in Figs. 1 and 2; and in Figs. 5 and 6 I have shown two ways in which an adapter embodying my invention may be applied to an ordinary plano-convex spherical lens.

In Fig. 5 reference character 6' represents an ordinary plano-convex spherical lens intended to be mounted in a bezel in the same manner as the lens 6 shown in Figs. 1 and 2. In order to secure an adapter such as shown in Figs. 1 and 2 to the lens 6', the latter may be provided on its inner side and adjacent its periphery either with an an-

nular groove or with spaced recesses corresponding in number to the number of legs or rods of the adapter, for receiving the free ends of the latter. In this figure reference character 31 represents either such a groove or such a recess. On positioning the free ends of the rods or legs 12 (only one of which is shown) of the adapter within the annular groove or recesses 31 of the lens 6', and then tightening up the clamping ring of the bezel in which the lens is mounted, the lens will be secured firmly in the bezel and the adapter will be firmly and rigidly secured to the lens by reason of the shoulder of the bezel co-acting with the laterally extending resilient projections 14 carried by the collars or bosses 13 on legs 12, in the same manner as described above in connection with the construction shown in Fig. 1.

In Fig. 6 reference character 6'' represents a lens similar to the lens 6' of Fig. 5. The lens 6'', however, is not provided either with an annular groove or with recesses for receiving the free ends of the rods or legs of the adapter. In the form of adapter designed to be applied to the lens shown in this figure, each of the legs 12 (only one of which is shown) is preferably substantially rigid and provided adjacent its free end with a collar 13', having a peculiarly formed substantially rigid projection 14'. Each of these projections 14' preferably extends outwardly from the corresponding rod 12 then forwardly at 32 a slight distance and then inwardly in the form of an arm 33 overlapping but spaced from the adjacent end of the rod 12. The peripheral portion of the lens 6'' is adapted to be received between the ends of the rods 12 and the adjacent arms 33 of the projections 14', the projections 14' being so formed that when the lens is so positioned the edge thereof will firmly engage the portions 32 of the projections whereby relative lateral movement of the lens and frame is prevented. A headed screw 34 is threaded through each of the arms 33 and after the lens 6'' is positioned as described, these screws are turned up tight. The legs 12 may be sufficiently resilient to permit the lens 6'' to be sprung into position; or one or more of the collars 13' may be removably secured to the corresponding rod or rods 12, as by means of a set-screw or set-screws, as indicated at 35, in order that the lens may be readily positioned between the free ends of the rods and the arms 33 of the projections 14'.

It will be apparent that the adapter will thus be rigidly and directly secured to the lens 6'' in fixed position with respect thereto and will be wholly supported therefrom independently of the usual bezel or other mounting for the lens.

While I have shown and described several

modifications of my invention, it is to be understood that the same is also subject to numerous other changes and modifications without any departure from the spirit of my invention or the scope of the appended claims.

Having now fully described my invention, what I claim as new and desire to protect by Letters Patent, is as follows:

10. 1. In combination, a semaphore lens, a lamp fixture comprising a tripod the legs of which are rigidly positioned at one end in one of the annular grooves of the lens, said fixture being thus supported directly and solely from said lens, and a lamp mounted on said fixture, substantially as described.
15. 2. In combination, a semaphore lens, a tripod the legs of which are slightly resilient and fixed at one end only, said legs being sprung at the other end into one of the annular grooves of the lens, and a lamp mounted for universal adjustment on said tripod, substantially as described.
20. 3. In combination, a semaphore lens, a lamp fixture having a plurality of legs connected at one end only, said legs being rigidly positioned at their other end in one of the annular grooves of the lens, the lamp fixture being thus supported directly and solely from said lens, and a lamp mounted on said fixture, substantially as described.
25. 4. In combination, a semaphore lens, a lamp fixture having a plurality of resilient spaced legs rigidly connected at one end only, said legs being sprung at their other end into one of the annular grooves of the lens, and a lamp mounted on said fixture, substantially as described.
30. 5. In combination, a semaphore lens, a frame having a plurality of resilient spaced legs fixed at one end only, said legs being sprung at their free end into one of the annular grooves of the lens, means for rigidly securing said frame in fixed position to said lens with the legs thereof at their free end positioned as specified, and a lamp mounted

for universal adjustment on said frame, substantially as described.

6. In combination, a semaphore lens, a bezel in which said lens is mounted, a lens clamping member cooperative with said bezel and adjustable to grip said lens firmly in said bezel, a frame comprising a plurality of legs connected at one end only, the free ends of said legs being positioned in one of the annular grooves of said lens, said legs being provided at their free ends with projections extending between said bezel and lens whereby when said member is adjusted to grip said lens in the bezel said frame will be rigidly secured to the lens, and a lamp mounted on said frame, substantially as described.

7. In combination, a semaphore lens, a bezel in which said lens is mounted, a lens clamping member cooperative with said bezel and adjustable to grip said lens firmly in said bezel, a frame comprising a plurality of resilient spaced legs fixed at one end only, the free ends of said legs being sprung into one of the annular grooves of said lens, said legs being provided adjacent their free ends with projections extending between said bezel and lens whereby when said member is adjusted to grip said lens in the bezel said frame will be rigidly secured to the lens, and a lamp mounted on said frame, substantially as described.

8. In combination, a casing having a light emitting opening, a lens therefor, a frame having a plurality of spaced legs connected at one end, said legs being fixedly secured at their other end to said lens, said frame being supported directly and solely from said lens by having its legs thus secured to the lens, a lamp mounted on said frame and means to fasten said legs and lens within said light emitting opening, substantially as described.

This specification signed this 20th day of February, 1920.

SELDEN G. WARNER.
